UNITED STATES PATENT OFFICE

2,096,917

MINING MACHINE

Thomas E. Pray, Chicago, Ill., assignor to Goodman Manufacturing Company, Chicago, Ill., a corporation of Illinois

Application October 7, 1935, Serial No. 43,855

14 Claims. (Cl. 262—28)

This invention relates to improvements in mining machines and more particularly to improvements in the cutting mechanism of a mining machine of the double cutter bar type adapted to cut an entire dirt band from a coal seam.

My invention has as one of its objects to provide a new and improved cutting mechanism of a novel construction arranged to cut a plurality of parallel-spaced kerfs and cut a connecting kerf perpendicular to these kerfs at the end thereof by positioning a novel form of rotatable cutting element between a pair of parallel-spaced cutter bars adjacent the forward end thereof and driving said cutting element therefrom in a novel manner. Another object of my invention is to provide a novel supporting connection for the rotatable cutting element and permit driving of the same when the bars are in misalignment with respect to each other. Still another object of my invention is to provide a new and improved construction of rotatable cutting element arranged in a novel, efficient and simple manner which includes an improved and efficient means for detachably holding the cutting element bits therein.

My invention may be more clearly understood with reference to the accompanying drawings wherein:

Figure 1 is a top plan view of a mining machine of a type which may have my invention embodied therein;

Figure 2 is an enlarged fragmentary side elevation of the forward portion of the machine shown in Figure 1 with certain parts broken away and shown in substantially longitudinal section;

Figure 3 is an enlarged view of the forward portion of the cutting mechanism, showing said cutting mechanism in substantially longitudinal section;

Figure 4 is a sectional view taken substantially along line 4—4 of Figure 3;

Figure 5 is a sectional view taken substantially along line 5—5 of Figure 4;

Figure 6 is a sectional view taken substantially along line 6—6 of Figure 2; and

Figure 7 is a detail view of one of the rotatable cutting element bit holding means.

In the drawings, the embodiment of my invention illustrated is preferably shown as applied to a mining machine of the track-mounted bottom cutting type. Said machine is of an ordinary construction and includes a track-mounted truck 18 having a turntable 11 at the forward end thereof. Said turntable has a cutting element 12 supported thereon on parallel-spaced trunnion supports 13, 13 extending therefrom. Said cutting element includes a cutter frame 15 pivotally mounted on said trunnion supports and extending forwardly beyond the forward end of said turntable and truck. A motor 14 is mounted on and extends rearwardly of said frame and a pair of parallel-spaced cutter

bars 16 and 17 project forwardly therefrom. Said cutter bars have cutter chains 18 and 19, respectively, movable thereabout and driven therearound by a pair of spaced coaxially arranged drive sprockets 20, 20.

While the frame 15 may have the cutter bars 16 and 17 directly connected thereto, said cutter bars are herein shown as being mounted on a cutter bar support member 21. Said cutter bar support member is journaled in a frame member 22 for pivotal movement with respect thereto about an axis coaxial with the axis of rotation of the drive sprockets 20, 20. Said last-named frame member is in turn supported for adjustable movement towards and away from the frame 15 for adjusting the cutting position of said cutter bars in a manner well known to those skilled in the art.

The drive from the motor 14 to the cutter chain drive sprockets 20, 20 includes an extensible drive connection, indicated generally by reference character 23, and illustrated in Figure 2, and is of a construction well known to those skilled in the art, so will not herein be described in detail.

The cutter bars 16 and 17 are of a usual construction having continuous gibbed channeled guides extending along opposite sides and around the forward end thereof for guiding the cutter chains thereabout. Said cutter bars are secured together in parallel relation with respect to each other by means of a spacing member 24 disposed therebetween and secured thereto by a cap screw 25 in a usual manner. Said cutter bars, together with said spacing member, are adjustably mounted on a forward supporting projection 26 from the cutter bar support member 21 by means of suitable nuts and bolts 27, 27. Said bolts depend from said supporting projection and extend through suitable slots formed in said cutter bars and spacing member so said cutter bars may be simultaneously adjusted, to take up slack in the cutter chains, by means of a suitable adjusting screw 28 in a usual manner.

Referring now particularly to several of the novel features of my invention, a rotatable cutting element 39 is mounted at the forward end of the cutter bars 16 and 17 in a manner which will hereinafter more clearly appear. Said cutting element is driven from one of the cutter chains at a speed greater than the speed of said cutter chains in order to enable said cutting element, which has a less effective diameter than said cutter chains as they round the forward end of the cutter bar, to cut as efficiently as said cutter chains.

As herein shown, said cutting element is driven from the lower cutter chain 19 which meshes with and drives a sprocket 31 journaled in the forward end of the cutter bar 17. Said sprocket 60

is formed integral with an annular ring 29, the inner periphery of which is journaled on suitable spaced-apart ball bearings 32, 32 mounted on lugs 33, 33 extending inwardly from opposed forward end plates 34, 34 of the cutter bar 17 (see Figures 3, 4, and 5). As herein shown, the upper end plate 34 has one ball bearing mounted on an inwardly extending lug 33, which bearing is adapted to engage the upper portion of the inner periphery of the annular ring 29. The lower plate 34 has two spaced-apart ball bearings mounted on the inwardly extending lugs 33, 33 which are adapted to engage the lower portion of the inner periphery of said annular ring.

15 Said end plates are secured to and extend forwardly of said cutter bar in a suitable manner and are further secured together by suitable cap screws 35, 35 extending through and threaded within the lugs 33, 33 which carry the ball bearings 32, 32 (see Figures 3 and 5). The portions of the end plates 34, 34 opposite the lugs 33, 33 are provided with lugs 36, 36 similar to the lugs 33, 33 which are adapted to abut the lugs 33, 33 and be engaged by the shouldered inner periphery of the sprocket 31 to form a bearing and guiding means for said sprocket.

30 An internal gear 37 is cut integral with and extends inwardly from the inner periphery of the annular ring 29 adjacent the central portion thereof in the space between the surface where the ball bearings 32, 32 and lugs 36, 36 engage said annular ring. Said gear is adapted to mesh with and drive a spur pinion 39. Said spur pinion is journaled on its hub in the end plates 34, 34 on suitable ball bearings 40, 40 mounted in said end plates on opposite sides of the teeth of said gear (see Figure 3). Said spur pinion is provided with a splined driving member 41 extending upwardly therefrom and herein shown as being formed integral therewith which forms a drive means for the rotatable cutting element 30.

45 The upper cutter bar 16 is provided with a pair of forwardly extending oppositely disposed end plates 43, 43 secured thereto by means of suitable nuts and bolts 44, 44 in the usual manner. Said end plates form an arcuate guide for reversing the direction of travel of the cutter chain 18 at the forward end of the cutter bar and form a bearing support means for an idler guide member 45 supported on suitable ball bearings 46, 46 mounted within said end plates. As herein shown, said idler guide member has a depending splined portion 47 adapted to form a guiding support for the upper portion of the rotatable cutting element 30.

60 The rotatable cutting element 30 includes a cylindrical member 49 of a hollow construction provided with internal splines 50 adapted to be loosely engaged by the splined driving member 41. Said cylindrical member is also provided with internal splines 51 adjacent the upper end thereof adapted to be loosely engaged by the splined portion 47 of the idler guide member 45. Thus, said cylindrical member may be axially moved with respect to said guide or drive member and may be driven from the spur pinion 39 when displaced axially with respect thereto in cases where the cutter bars are in a misaligned position with respect to each other, which condition frequently occurs when one cutter bar is cutting in harder material than the other.

65 A threaded rod 53 is connected between the forward ends of the cutter bars 16 and 17 to aid in holding said cutter bars in alignment with

respect to each other. Said threaded rod extends through the idler member 45, cylindrical driving member 49 and spur pinion 39 and is threaded within a threaded boss 54 formed integral with the lower end plate 34 (see Figure 3). A suitable nut 55 is threaded on the upper end of said threaded rod and engages the upper end plate 43. It may be seen in Figure 3 that considerable play is provided between said threaded rod and the rotating parts of the cutting element 30 coaxial therewith to permit axial movement of said parts with respect to said rod about a transverse axis and permit driving of said parts when there is weaving motion of said cutter bars with respect to each other.

15 It may thus be seen that the rotatable cutting element 30 is driven from the lower cutter chain 19 at a speed greater than the speed of said chain in a simple and efficient manner and that the support for said cutting element is such as 20 to prevent binding of the parts when the cutter bars are in a misaligned position with respect to each other.

25 Referring now in particular to the novel construction of the cutting portion of the rotatable cutting element 30; the lower portion of the cylindrical member 49 is herein shown as being provided with a plurality of jaws 56, 56 which are adapted to engage corresponding jaws formed in the lower portion of a bit holding 30 member 57. Said bit holding member is bored in its central portion and slidably engages the outer periphery of said cylindrical member. A pair of projections or wings extend outwardly from the central portion of said bit holding member in opposite directions, and each of said projections have a bit receiving slot 59 formed therein. Each of said slots is adapted to receive an oppositely disposed cutter bit 60 of a usual construction so that the points thereof 40 may present a cutting surface upon rotation of the member 49 (see Figures 3 and 6).

35 The depth of the bit receiving slots 59, 59 is equal to half the thickness of the cutter bits 60, 60 so that half of each of said cutter bits 45 project above the upper surface of said bit holding member and may be engaged by suitable bit receiving slots formed in the under surface of a bit holding and spacing member 63. Said bit holding and spacing member is of a construction 50 similar to the bit holding member 57, with the exception that it is provided with another set of projections 64, 64, extending therefrom in a different angular direction than the set of projections engaging the upper surface of the cutter 55 bits 60, 60. Said projections are provided with bit receiving slots 64a, 64a in the upper surface thereof similar to the bit receiving slots 59, 59 which are adapted to receive the cutter bits 60, 60 (see Fig. 7).

60 In a like manner, another bit holding and spacing member 65 is provided which is similar to the bit holding and spacing member 63. Said bit holding member has a pair of oppositely disposed projections adapted to engage the upper 65 half of the cutter bits 60, 60 mounted in the projections 64, 64 of the bit holding and spacing member 63. Another set of bit holding projections extend angularly from the upper portion of the bit holding member 65 and are adapted to 70 carry cutter bits 60, 60 in suitable projections extending from the upper surface thereof which bits are adapted to be engaged by slots formed in the under surface of another bit holding and spacing member. Any number of other similar 75

bit holding and spacing members may be provided along the member 49 depending upon the effective cutting length thereof, but as herein shown two more of said members are provided which include a bit holding and spacing member 66 which is the last of these bit holding members. Said bit holding member is abutted by an upper bit holding member 67 which is similar to the lower bit holding member 51, with the exception that it does not have jaws formed therein. Said upper bit holding member is adapted to be engaged by a nut 69 threaded on the upper end of the cylindrical member 49. Said nut forms a clamping means for clamping all of the bit holding and spacing members together and holding the bits in their respective slots whereby rotation of the lower bit holding member 57 will cause rotation of all of said bit holding members as a unit. It should be noted with reference to Figure 6, that the projections of said bit holding members, which hold the bits 60, project from the center of the cutting element in various angular relationships with respect to each other so as to present a continuous cutting surface therearound and form a unitary rotatable cutting unit.

While I have herein shown and described one form in which my invention may be embodied, it will be understood that the construction and arrangement of the various parts may be changed or altered without departing from the spirit and scope thereof. Furthermore, I do not wish to be construed as limiting myself to the precise construction illustrated, excepting as it may be limited in the appended claims.

I claim as my invention:

1. In combination in a mining machine, a projecting cutter bar having a cutter chain movable thereabout and adapted to cut a kerf in a mine wall, a rotatable cutting element at the forward end of said cutter bar adapted to cut a kerf perpendicular to the kerf cut by said cutter bar, said cutting element having a plurality of bits projecting therefrom having an effective cutting diameter less than the width of said cutter bar, and a drive connection from said cutter chain to said rotatable cutting element for driving said cutting element at a greater speed than the speed of said cutter chain.

2. In combination in a mining machine, a projecting cutter bar having a cutter chain movable thereabout and adapted to cut a kerf in a mine wall, a rotatable cutting element at the forward end of said cutter bar adapted to cut a kerf perpendicular to the kerf cut by said cutter bar, said cutting element having a plurality of bits projecting therefrom having an effective cutting diameter less than the width of said cutter bar, and a drive connection from said cutter chain to said rotatable cutting element for driving said cutting element at a greater speed than the speed of said cutter chain including a sprocket journaled in said cutter bar and driven by said cutter chain, an internal spur gear driven by said sprocket and a spur pinion journaled in said cutter bar and driven by said internal gear.

3. In combination in a mining machine, a pair of parallel-spaced projecting cutter bars having cutter chains movable thereabout, and means disposed between said cutter bars at the forward end thereof and driven by one of said cutter chains for cutting a kerf perpendicular to the kerfs cut by said cutter bars comprising a rotatable cutting element having a plurality of bits projecting therefrom having an effective

cutting diameter less than the width of said cutter bar, said rotatable cutting element having a relatively loose bearing connection with one of said cutter bars, and a drive connection from the cutter chain on the other of said cutter bars to said rotatable cutting element for driving said cutting element at a greater speed than the speed of said cutter chain.

4. In combination in a mining machine, a pair of parallel-spaced projecting cutter bars having cutter chains movable thereabout, and means disposed between said cutter bars at the forward end thereof and driven by one of said cutter chains for cutting a kerf perpendicular to the kerfs cut by said cutter bars comprising a rotatable cutting element having a plurality of bits projecting therefrom having an effective cutting diameter less than the width of said cutter bar, and a drive connection from one of said cutter chains to said rotatable cutting element for driving said cutting element at a greater speed than the speed of said cutter chain including a sprocket journaled in one of said cutter bars and driven by the cutter chain associated therewith, an internal spur gear driven by said sprocket, and a spur pinion driven by said internal gear and having driving connection with said cutting element.

5. In combination in a mining machine, a pair of parallel-spaced projecting cutter bars having cutter chains movable thereabout, and means disposed between said cutter bars at the forward end thereof and driven by one of said cutter chains for cutting a kerf perpendicular to the kerfs cut by said cutter bars comprising a rotatable cutting element having a plurality of bits projecting therefrom having an effective cutting diameter less than the width of said cutter bar, and a drive connection from one of said cutter chains to said rotatable cutting element for driving said cutting element at a greater speed than the speed of said cutter chain including a sprocket journaled in one of said cutter bars and driven by the cutter chain associated therewith, an internal spur gear driven by said sprocket, and a spur pinion driven by said internal gear and having a relatively loose driving connection with said cutting element.

6. In combination in a mining machine, a pair of parallel-spaced projecting cutter bars having cutter chains movable thereabout, and means disposed between said cutter bars at the forward end thereof and driven by one of said cutter chains for cutting a kerf perpendicular to the kerfs cut by said cutter bars comprising a rotatable cutting element having a plurality of bits projecting therefrom having an effective cutting diameter less than the width of said cutter bar, and a drive connection from one of said cutter chains to said rotatable cutting element for driving said cutting element at a greater speed than the speed of said cutter chain including a sprocket journaled in one of said cutter bars and driven by the cutter chain associated therewith, an internal spur gear driven by said sprocket, and a spur pinion driven by said internal gear and having a relatively loose splined driving connection with said cutting element.

7. In a mining machine, a cutter bar having a cutter chain movable thereabout and normally adapted to cut a horizontal kerf in the mine wall, and means at the forward end of said cutter bar driven by said cutter chain for cutting a kerf perpendicular to the kerf cut by said cutter

chain comprising a rotatable cutting element mounted at the forward end of said cutter bar and extending therefrom, said cutting element having a plurality of bits detachably mounted 5 therein and said drive from said cutter chain to said cutting element including a sprocket journaled in the forward end of said cutter bar having a spur gear formed internally thereof, and a pinion journaled in said cutter bar and 10 driven by said internal gear for driving said cutting element.

8. In a mining machine, a projecting cutter bar having a cutter chain movable thereabout, and means at the forward end of said cutter bar 15 driven by said cutter chain for cutting a kerf perpendicular to the kerf cut by said cutter bar and chain comprising a rotatable cutting element mounted at the forward end of said cutter bar and extending therefrom in a plane perpendicular to the plane of travel of said cutter chain, said cutting element having a plurality of bits projecting therefrom, and a drive connection from said cutter chain to said cutting element including a sprocket driven by said cutter chain 20 and journaled in the forward end of said cutter bar, a gear formed internally of said sprocket and a pinion journaled in said cutter bar and driven by said gear and operatively connected 25 with said cutting element.

30 9. In a mining machine, a plurality of parallel-spaced cutter bars having cutter chains movable thereabout, and means disposed between said cutter bars at the forward end thereof for cutting a kerf perpendicular to the kerfs cut by said cutter bars comprising a rotatable cutting element having a relatively loose supporting connection with 35 said cutter bars and having a plurality of bits projecting therefrom, and a drive connection from one of said cutter chains to said cutting element including a sprocket journaled in the forward 40 end of one of said cutter bars, a drive connection from the chain associated with said bar to said sprocket, a gear formed internally of said sprocket, and a pinion journaled in said cutter 45 bar driven by said gear and having driving connection with said cutting member.

10. In combination in a mining machine, a pair of parallel-spaced projecting cutter bars having cutter chains movable thereabout, and means 50 disposed between said cutter bars at the forward end thereof and driven by said cutter chains for cutting a kerf perpendicular to the kerfs cut by said cutter bars comprising a rotatable cutting element having a plurality of bits projecting 55 therefrom, said cutting element having splined ends, one of said splined ends being adapted to be loosely engaged by a splined member journaled in and extending from one of said cutter bars, and the other of said ends being adapted to be 60 loosely engaged by a splined member journaled in and extending from said other cutter bar whereby said cutting element may be driven from one of said splined members when in various axial 65 positions with respect thereto.

65 11. In combination in a mining machine, a pair of parallel-spaced projecting cutter bars having cutter chains movable thereabout, and means disposed between said cutter bars at the forward end thereof and driven by said cutter chains for 70 cutting a kerf perpendicular to the kerfs cut by said cutter bars including a rotatable cutting element having a plurality of bits projecting there-

from, said cutting element having splined ends, one of said splined ends being adapted to be loosely engaged by a splined member journaled in and extending from one of said cutter bars, and the other of said ends being adapted to be loosely engaged by a splined member journaled in and extending from said other cutter bar whereby 5 said cutting element may be driven from said last-named splined member when in various axial positions with respect thereto, said last-named 10 splined member having a gear thereon and said gear being driven by an internal gear journaled in said last-named cutter bar and driven from the cutter chain movable thereabout.

12. In combination in a mining machine, a pair 15 of parallel-spaced projecting cutter bars having cutter chains movable thereabout, and means disposed between said cutter bars at the forward end thereof and driven by said cutter chains for cutting a kerf perpendicular to the kerfs cut by 20 said cutter bars including a rotatable cutting element having a plurality of bits projecting therefrom, said cutting element having an end adapted to be loosely engaged by a member extending from one of said cutter bars and having an opposite 25 end which is splined and is adapted to be loosely engaged by a splined driving member journaled in and extending from said other cutter bar whereby said cutting element may be driven from said driving member when in misalignment 30 with respect thereto.

13. In combination in a mining machine, a pair of parallel-spaced projecting cutter bars having cutter chains movable thereabout, and means disposed between said cutter bars at the forward end 35 thereof and driven by said cutter chains for cutting a kerf perpendicular to the kerfs cut by said cutter bars including a rotatable cutting element having a plurality of bits projecting therefrom, said cutting element having an end adapted to be 40 loosely engaged by a member extending from one of said cutter bars and having an opposite end which is splined and is adapted to be loosely engaged by a splined driving member journaled in and extending from said other cutter bar, whereby 45 said cutting element may be driven from said driving member when in misalignment with respect thereto, said driving member having a gear thereon and said gear being driven by an internal gear journaled in said last-named cutter bar and 50 driven from the cutter chain movable thereabout.

14. In combination in a mining machine, a pair of parallel-spaced projecting cutter bars having cutter chains movable thereabout, and means disposed between said cutter bars at the forward end thereof and driven by said cutter chains for cutting a kerf perpendicular to the kerfs cut by 55 said cutter bars including a rotatable cutting element having a plurality of bits projecting therefrom, said cutting element having an end adapted to be loosely engaged by a member extending from one of said cutter bars and having an opposite end which is splined, a sprocket journaled in the forward end of said other cutter bar and adapted to be driven by the cutter chain movable thereabout, an internal gear formed integral with said sprocket, and a spur gear on said splined driving member adapted to be driven by said internal gear. 70

THOMAS E. PRAY.
